Primary Examiner — Eric Goodman*Assistant Examiner* — Luqman McNeil(74) *Attorney, Agent, or Firm* — Blakely Sokoloff Taylor & Zafman(57) **CLAIM**

The ornamental design for a pressure washer, as shown and described.

DESCRIPTION

FIG. 1 is a perspective front, top and first side view illustrating the new design.

FIG. 2 is a second side elevational view thereof.

FIG. 3 is front elevation view thereof.

FIG. 4 is a first side elevation view thereof.

FIG. 5 is a rear elevation view thereof; and,

FIG. 6 is a top plan view thereof.

The broken line showing of details in FIGS. 1 to 6 is included for the purpose of showing environmental portions of the design. No claim is made to the portions shown in broken line.

1 Claim, 6 Drawing Sheets(56)
